US00D882367S

(12) **United States Design Patent** (10) Patent No.: **US D882,367 S**
(45) Date of Patent: **** Apr. 28, 2020**

(54) **VACUUM SHROUD ATTACHMENT**

(71) Applicant: **Skitter & Squirt Adventures, LLC**,
Missoula, MT (US)

(72) Inventor: **Jack M King, Jr.**, Phoenix, AZ (US)

(**) Term: **15 Years**

(21) Appl. No.: **29/671,005**

(22) Filed: **Nov. 21, 2018**

(57) **CLAIM**

The ornamental design for a vacuum shroud attachment, as
shown and described.

DESCRIPTION

FIG. 1 depicts an isometric view of the vacuum shroud
attachment from above and to the side whilst it is coupled to
a vacuum shroud.

FIG. 2 depicts an isometric view of the vacuum shroud
attachment from an above and to the opposite side than FIG.
1 whilst it is coupled to a vacuum shroud.

FIG. 3 depicts a back view of the vacuum shroud attachment
coupled to a vacuum shroud.

FIG. 4 depicts a front view of the vacuum shroud attachment
coupled to a vacuum shroud.

FIG. 5 depicts a view of the vacuum shroud attachment from
above and angled in front on its own.

FIG. 6 depicts a view of the vacuum shroud attachment from
above and angled behind on its own.

FIG. 7 depicts a view of the vacuum shroud attachment from
below and angled behind on its own.

FIG. 8 depicts a view of the vacuum shroud attachment from
below and angled in front on its own.

FIG. 9 depicts an exploded view of the vacuum shroud
attachment from above and to the side.

FIG. 10 depicts an exploded view of the vacuum shroud
attachment from below and to the side.

FIG. 11 depicts an exploded view of the vacuum shroud
attachment from directly above; and,

FIG. 12 depicts an exploded view of the vacuum shroud
attachment from directly below.

The broken line showing of a vacuum shroud is included for
the purpose of illustrating environmental structure only and
forms no part of the claimed design.

1 Claim, 9 Drawing Sheets
